[57] CLAIM

The ornamental design for a deep fat fryer, as shown and described.

DESCRIPTION

FIG. 1 is a perspective view of a deep fat fryer showing my new design;
FIG. 2 is a top plan view thereof;
FIG. 3 is a front elevation thereof;
FIG. 4 is a rear elevation;
FIG. 5 is a left side elevation;
FIG. 6 is a bottom plan view; and,
FIG. 7 is an exploded perspective view showing the lid raised and the basket and reservoir removed to more clearly reveal the shape of the interior surfaces.

Only one basket has been shown in FIG. 7 for convenience of illustration.
